UNITED STATES PATENT OFFICE

HENRY C. REUTER, OF CHICAGO, ILLINOIS

DESIGN FOR A FRAME FOR WINDOWS OR THE LIKE

Application filed June 14, 1929. Serial No. 31,680. Term of patent 7 years.

To all whom it may concern:

Be it known that I, HENRY C. REUTER, a citizen of the United States, residing at Chicago, in the county of Cook and State of Illinois, have invented a new, original, and ornamental Design for Frames for Windows or the Like, of which the following is a specification, reference being had to the accompanying drawing, forming a part thereof.

I claim:

The ornamental design for a frame for windows or the like, as shown.

HENRY C. REUTER.
